UNITED STATES PATENT OFFICE.

CHARLES AYERS, OF FARMINGTON CENTRE, WISCONSIN.

IMPROVEMENT IN FENCE-POSTS.

Specification forming part of Letters Patent No. 117,963, dated August 15, 1871.

To all whom it may concern:

Be it known that I, CHARLES AYERS, of Farmington Centre, in the county of Polk and State of Wisconsin, have invented a new and Improved Metal Fence-Post; and I do hereby declare that the following is a full, clear, and exact description thereof, which will enable others skilled in the art to make and use the same, reference being had to the accompanying drawing forming part of this specification, which represents a perspective view of my improved fence-post.

This invention relates to a new post for wire, board, or picket-fences; and consists in casting the same of metal with a continuous flange, retaining-rib, and of peculiar form, all with the object of making it light, strong, and inexpensive.

A in the drawing represents the fence-post, cast, of iron or other metal, so that its lower end has the shape of a spear-head, as shown. A continuous projecting flange, *a*, is formed on the post along the edge of the same, and serves to

considerably strengthen it, permitting the use of weaker material for the body *b*. The flange serves, also, to hold the fence-rails or boards, if such are used, laterally in place, and is perforated to receive the fastening-pins or the wires for a wire fence. The spur-shaped lower end of the post enters the ground entirely, as shown, and serves to properly steady it in every direction. A projecting rib, *c*, is formed on the face of the post between the flange on the spear, to add to the strength and stability of the device.

Having thus described my invention, I claim as new and desire to secure by Letters Patent—

A cast-metal fence-post, spear-shaped at the lower end and provided with the flange *a* and rib *c*, as set forth.

CHARLES AYERS.
